(57) **CLAIM**

The ornamental design of a control panel for a vehicle, as shown and described.

DESCRIPTION

FIG. 1 is an upper top left side isometric view of a control panel for a vehicle, in accordance with the present disclosure;

FIG. 2 is an upper top right side isometric view of the control panel of FIG. 1, in accordance with the present disclosure; FIG. 3 is a side view of the bottom side of the control panel of FIG. 1, in accordance with the present disclosure;

FIG. 4 is a side view of the top side of the control panel of FIG. 1, in accordance with the present disclosure;

FIG. 5 is a downward view of the top surface of the control panel of FIG. 1, in accordance with the present disclosure;

FIG. 6 is an upward view of the bottom surface of the control panel of FIG. 1, in accordance with the present disclosure;

FIG. 7 is a longitudinal left side view of the control panel of FIG. 1, in accordance with the present disclosure;

FIG. 8 is a longitudinal right side view of the control panel of FIG. 1, in accordance with the present disclosure;

FIG. 9 is a bottom right side isometric view of the control panel of FIG. 1, in accordance with the present disclosure; and,

FIG. 10 is a bottom left side isometric view of the control panel of FIG. 1, in accordance with the present disclosure.

Broken lines used in the figures to illustrate a handle, such as a parking brake handle for a vehicle, is for the purpose of depicting the control panel as it would be installed or otherwise disposed on the handle and forms no part of the claimed design.

Broken lines used in the figures to illustrate text and other graphics is for the purpose of depicting to a user how the control panel might display graphics and forms no part of the claimed design.

The nature and intended use of the article in which the design is embodied is for the occasion of a driver desiring to control one or more functions of a vehicle via simple touch operation of a control panel. The control panel may be installed on or otherwise disposed around a vehicle component, such as the handle of a parking brake.
